UNITED STATES PATENT OFFICE.

PHILIP A. RENTA, OF NEW YORK, N. Y.

ELECTRIC-CAR-CONTROL APPARATUS.

Application filed August 17, 1925. Serial No. 50,566.

This invention relates to improvements in electric car control apparatus and the method of operation thereof, and has for its principal object, to provide a mechanism of this character which shall cause all current passing through the contacts thereof to be distributed therefrom in one direction of flow without regard to the polarity in which it is received.

10 Another object is to make possible the operation of cars on the "metallic circuit" system with the same simplicity and safety as is the case when the "ground return" method is used, but without any change in the apparatus except the introduction of this device into the circuits thereof.

15 Another object is the elimination of a number of cutouts, fuses, circuit breakers etc. which occur in the return, or "low" side of the circuit.

20 A further object is to provide a method of operation adapted for use with the mechanism hereinafter described and shown in the accompanying drawings.

25 Other objects and advantages of this invention will be disclosed and explained in detail in the following specification.

Referring to the drawings:

30 Figure 1 shows a diagram of the device claimed, connected in circuit with a car-wiring diagram of a type in general use where the "metallic circuit" system is in operation.

35 Figure 2 shows another diagram of the device with a limited portion of the car-wiring system, the circuit breakers etc. being connected in parallel in this case.

40 Figure 3 shows a plan view of a car with positions of controller, motors, plow etc. indicated thereon.

45 The main elements of the device claimed, are as follows: an armature 10 located between pole pieces 11 and 12, has extending therefrom an arm 13, attached to which and insulated from which are contact plates 14—15—16—17—18 and 19 adapted to connect with the points as shown at 20—21—22—23—24—25—26— and 27 etc. Springs 28 and 29 serve to hold the arm 13 in open position when the arm 13 is not controlled by current passing through the armature 10. Additional contacts as shown at 30 and 31 may be added to contact with the switch arm 13 if desired for connection to other apparatus.

50 For reference purposes some of the chief elements of the car-wiring diagram shown herewith are enumerated as follows, al-

though these said elements are not parts of the device here claimed. Power rails 38 and 39, contact shoes 40 and 41, plugs 42 and 43, circuit breakers 44 and 45, switches 46 and 47, door contacts 48—49, foot switches 50 60 and 51, controllers 52 and 53, motors 54 and 55, overload relay 56, resistances as indicated at 57 and 58, fuses as at 59 and 60, and plow as at 61. The device as shown is equipped with permanently magnetized pole pieces; 65 these however, may be electro-magnetic when that form is best suited to the requirements.

In further explanation of the device and its relation to the car control system, it may be said that it is located preferably under 70 the floor and in proximity to the "plow plugs" replacing the "main line switch" which is eliminated by its use. Referring to Fig. 1 of the drawings a wire connects the contact shoe 41 now positive, or "T¹" as 75 termed in the trade for positive to the plug 43 and from thence the circuit is carried over the wire 37 to the contact point 22, from whence it crosses to the contact 25 which connects through the plate 18 with 80 the contact 27, from which point the circuit extends to the circuit breaker 44 from which it further extends through the second circuit breaker 45 and on through the controller 52 or 53 and the motors back to the 85 contact point 21 and from thence to points 23 and 24 from which it continues through the plug 42 to the contact shoe 40 and the rail 39. The circuit illustrated in Figure 2 of the drawings is similar to that above 90 described except that the current is divided after leaving the contact 27 and extends therefrom to the circuit breakers 44 and 45 in parallel, from which it passes through the motors etc. back through the negative 95 or "T²" as termed in the trade for negative.

The switches 46 and 47 with the door contacts as shown at 48 and 49 together with foot switches 50 and 51 are all in series with the armature 10, thus providing against the 100 starting of the car, should any door be open, or other switch out of contact, as in that event the current would be cut off from the said armature and the switch arm 13 would be swung into neutral position by the springs 105 28 and 29. In this position, it is obvious that no current could pass to the operating mechanism of the car. It will be seen that as long as the polarity of the current remains the same the switch arm 13 will be 110 held in contact with the points above de-

scribed by reason of the magnetic action of the armature 10, but should the polarity be changed, as frequently occurs in the use of the "metallic circuit" system, then the 5 change of direction of current through the armature coil 10 will cause the arm 13 to swing over to the opposite set of contacts through which the positive current arriving at the contact 24 would pass through the 10 contact 26 and thence to the circuit breaker 44 at which point it will arrive having the same direction of flow as in the first instance. From thence it follows the same course as before up to its arrival at the point 15 20, from which it passes through the point 22 to the rail 38 which is now the negative conductor. The control circuit illustrated, differs somewhat in detail from those in operation on many railroads, they being subject to constant change due to the adoption 20 of new inventions and to improvements in general.

It is pointed out that contacts 20, 22, 24 and 26 may be considered as "one point" of 25 a "two point" switch, the "second point" being contacts 21, 23, 25 and 27. Furthermore relative to the main electrical conductors of the car, contacts 20 and 26 constitute double pole contacts, and similarly contacts 30 21 and 27 constitute second double pole contacts. As clearly shown on the drawing contacts 20 and 21 are connected in series relative to the first point and the second point of the two point switch, and contacts 26 and 35 27 are connected in series relative to the points of the same switch. Relative to the current collecting device of the car, contacts 22 and 24 constitute double pole contacts, and contacts 23 and 25 constitute second 40 double pole contacts. Contacts 23 and 24 are connected in series relative to the points of the switch, and contacts 22 and 25 are connected in series, also relative to the points of the switch. The arrangement of the contacts 20, 21, 26 and 27 is now defined as 45 one set of double pole, two point switch contacts, and the arrangement of the contacts 22, 23, 24 and 25 is now defined as a set of double pole, two point switch contacts. 50

Devices such as "speed limit relays", "limit switches", "dead man's valve" etc., may be connected in series with the device here shown when desired.

In addition to the above described advantages in the use of this device, it will also prevent many fires and accidents in car barns or the like, now caused by inexperienced workmen by reason of changes in polarity undetected by them in the course 60 of their work of cleaning and overhauling the cars.

It will be understood that this description and accompanying drawings serve to show my invention only in its preferred 65 form. Minor changes in construction etc.

may be adopted without sacrificing the scope of the claims thereof.

Having thus described my invention, what I claim as new and desire to secure by Letters Patent, is as follows:

1. In a device of the class described, the combination of car motors, power leads therefor, a polarized relay having a projecting contact arm, a pair of contacts on each side of the contact arm, stationary contacts straddling the contact arm and arranged four on each side, so that with the contact arm in one position, the pair of contacts on one side of the contact arm engage with the four stationary contacts on the same side, 75 and with the contact arm in another position the pair of contacts on the other side of the contact arm engage with the other four stationary contacts, every one contact on the contact arm being engageable with two adjacent contacts of the said stationary contacts, a connection from the first contacts of the said two rows of four contacts, counting from the end of the contact arm, to the current return of the car motors, a connection 80 from the fourth contacts of the said two rows of four contacts to the current supply of the car motors, a connection from the second contact of one row to the third contact of the other row and to one of the power leads, and another connection from the third contact to the second contact and to the other of the power leads, so that upon a change in polarity of the power leads, the contact arm moves from one position to another to not alter the polarity of the current supply to the same car motors. 85

2. In a device of the class described, the combination of electrical equipment, power leads therefor, a relay having a projecting contact arm, a pair of contacts on each side of the contact arm, stationary contacts straddling the contact arm and arranged four on each side, so that with the contact arm in one position, the pair of contacts on the contact arm engage with the four stationary contacts on the same side, and with the contact arm in another position the pair of contacts on the other side of the contact arm engage with the other four stationary contacts, every one contact on the contact arm being engageable with two adjacent contacts of the said stationary contacts, a connection from the first contacts of the said two rows of four contacts, counting from the end of the contact arm, to the current return of the electrical equipment, a connection from the fourth contacts of the said two rows of four contacts to the current supply of the electrical equipment, a connection from the second contact of one row to the third contact of the other row and to one of the power leads, and another connection from the third contact to the second contact and to the other of the power leads, so that upon a change in polar- 100 105 110 115 120 125 130

ity of the power leads, the contact arm moves from one position to another to not alter the polarity of the current supply to the electrical equipment.

5 3. In a device of the character described, a double pole current collecting device, main electrical conductors, a polarized relay with double pole contacts, and two sets of double pole two point switch contacts, one set being connected to the said double pole current collecting device, and the other set being connected to the said main electrical conductors, and arranged so that when one of the 10 points of the two sets of contacts is engaged 15 by the said double pole contacts of the polar-

ized relay, this group of contacts will be in double pole, series connection between the current collecting device and the main electrical conductors, and when the other point of the two sets of contacts is engaged by the 20 said double pole contacts of the polarized relay, the second set will be in double pole series connection between the same current collecting device and the main electrical conductors, for relaying the current to the said 25 main conductors always in one direction of flow.

In testimony whereof I have affixed my signature.

PHILIP A. RENTA.
